(57) **CLAIM**

The ornamental design for the baby booster seat, as shown and described.

DESCRIPTION

FIG. 1 is a front perspective view of the baby booster seat showing my new design in unfolded condition;

FIG. 2 is a front perspective view of the baby booster seat shown fully unfolded;

FIG. 3 is a front perspective view of the baby booster seat in a folded condition;

FIG. 4 is a rear perspective view of the baby booster seat in unfolded condition;

FIG. 5 is a left side elevation view of the baby booster seat in folded condition, the right side being a mirror image thereof; and,

FIG. 6 is a rear elevation view of the baby booster seat in unfolded condition.

The broken line showing of a chair is included for the purpose of illustrating environmental structure and forms no part of the claimed design.
